UNITED STATES PATENT OFFICE.

WILLIAM ANDREW McMECHAN, OF ST. CLAIRSVILLE, OHIO.

DESIGN FOR A TUBULAR LADDER-RUNG.

SPECIFICATION forming part of Design No. 26,744, dated March 9, 1897.

Application filed December 14, 1896. Serial No. 615,697. Term of patent 14 years.

To all whom it may concern:

Be it known that I, WILLIAM ANDREW McMECHAN, a citizen of the United States, residing at St. Clairsville, in the county of Belmont and State of Ohio, have invented a certain new and useful Design for a Tubular Ladder-Rung; and I do hereby declare the following to be a full, clear, and exact description of the invention, such as will enable others skilled in the art to which it appertains to make and use the same.

My invention relates to a design for a tubular ladder-rung.

It relates to the entire configuration of the rung.

My invention relates particularly to the ladder-rung as illustrated in the accompanying drawings, in which—

Figure 1 is a perspective view of the ladder-rung embodying my design. Fig. 2 is a transverse section through the rung about midway of its length.

The leading features of my design appear in the following description.

1 represents the tubular rung, the body of which corresponds to a horizontal ellipse in cross-section, as shown in Fig. 2, while the outer ends 2 2 are flaring or funnel-shaped, with their outer edges terminating in a vertical elliptical-shaped flange 3, as shown. 30

Having thus fully described my invention, what I claim as new, and desire to secure by Letters Patent of the United States, is—

The design for a tubular ladder-rung, substantially as herein shown and described. 35

In testimony whereof I affix my signature in presence of two witnesses.

WILLIAM ANDREW McMECHAN.

Witnesses:

ROBT. M. EATON,
GEORGE C. MCKEE.
